UNITED STATES PATENT OFFICE.

GOTTFRIED PLUMM, OF BERLIN, GERMANY.

SPRAY-CARBURETER.

1,031,147.

Specification of Letters Patent.

Patented July 2, 1912.

Application filed May 2, 1911. Serial No. 624,638.

To all whom it may concern:

Be it known that I, GOTTFRIED PLUMM, a subject of the German Emperor, and residing at Berlin, German Empire, have invented certain new and useful Improvements in Spray-Carbureters, of which the following is a specification.

My invention relates to improvements in spray-carbureters for internal-combustion engines, and has for its object the prevention of waste of the liquid fuel employed.

In carbureters having a crown-nozzle and revolving mixing mechanism considerable loss of fuel is occasioned through the liquid particles being caught up by the rotary mixing devices, and, by reason of the centrifugal force, thrown against the wall of the carbureter cylinder, down which they run unutilized. Waste also takes place owing to the formation of an empty conical space above the horizontally terminating nozzle-crown on which the revolving mixing devices are mounted, which space is not entered by the explosive mixture flowing toward the throttle-valve. Into this vacuum unvaporized particles of fuel are drawn, and settle on the horizontal surface of the nozzle-crown, finally flowing down its outside wall. Since only a very small part of these particles is vaporized by the ascending current of carbureted air, the waste is pronounced. With the object of obviating this loss of fuel, I avoid a vacuum above the nozzle-crown by the provision of a suitable conical structure, for instance a cone-shaped support for the revolving mixing devices, which also causes any particles of fuel which may settle upon it, like the particles caught up by the mixing devices themselves, to be thrown against the wall of the carbureter cylinder, whence all the particles are conducted in suitable manner to the inside wall of a porous nozzle-pipe which surrounds the nozzle-crown. The particles are absorbed by the porous material and are vaporized by the current of carbureted air flowing up over the same.

An embodiment of the invention is illustrated in the accompanying drawing, in which—

Figure 1 is a vertical section on the line I—II—III of Fig. 2, while Fig. 2 is a plan of the rim of the porous nozzle-pipe.

The finely divided liquid fuel from the crown-nozzle *a*, rushing through the apertures *b* in the walls of the chamber *n*, min-

gles in well-known manner within a nozzle-pipe *d* of wood or other suitable porous material, with the air entering at *c* and is vaporized. A part of those particles which remain unvaporized adheres to the wall of the nozzle-pipe *d* and is converted into vapor by the succeeding current of carbureted air; while another part is caught up by the beaters *f* and blades *g* of rotary pulverizing or mixing mechanism and hurled against the wall of the carbureter cylinder *A*. A third part of the unvaporized particles is deposited upon the carrier *h* of the beaters and blades, which is mounted on the head *e* and turns on ball-bearings *p*. The carrier is of cone shape, corresponding to the direction of flow of the current of carbureted air. This will especially be the case when the explosive mixture which has entrained these particles is deflected toward the center by the supplementary air entering at *m*. The liquid particles flow down toward the lower edge of the rotary cone *h* and having arrived there are likewise thrown against the wall of the carbureter cylinder *A*.

The upper edge or rim *i* of the porous nozzle-pipe *d* is preferably of metal and trends outward and upward, fitting close against the wall of the carbureter cylinder *A*. This rim *i* has an annular rib or fillet *i*¹ cast on it, and is furnished with holes *k* (Fig. 2) to admit passage of the supplementary air flowing in at *m*. Between the holes *k* grooves *l* are formed at intervals in the fillet *i*¹ for the purpose of conducting to the inner wall of the porous nozzle-pipe *d* the particles of liquid fuel which having been thrown against the walls of the carbureter *A*, run down it and collect in front of the fillet *i*¹. Arrived at the inside wall of the nozzle-pipe the particles are absorbed by the porous material and vaporized by the ascending current of carbureted air. In this manner there are no particles of liquid fuel wasted.

Having thus described my invention, I declare that what I claim is—

1. In a spray-carbureter, in combination, a nozzle-structure presenting a revolving conical top with mixing mechanism, and a porous nozzle-pipe, surrounding the said structure and constituting an air inlet, and adapted to conduct to its inside wall the entrained particles of liquid fuel thrown against the wall of the carbureter cylinder

by the said rotating parts, substantially as and for the purposes described.

2. In a spray-carbureter, in combination, a nozzle structure presenting a revolving 5 conical top with mixing mechanism, and a porous nozzle-pipe, surrounding the said structure and constituting an air inlet, whose upper rim trends upward and outward and fits close to the wall of the carbureter cylinder, so that entrained particles 10 of liquid fuel running down the cylinder wall may be conducted by the rim to the inside wall of the nozzle-pipe, substantially as and for the purposes described.

3. In a spray-carbureter, in combination, a chamber having main and supplementary air inlets, a nozzle-structure located therein and presenting a revolving conical top with mixing mechanism, and a porous nozzle-pipe, surrounding the said structure, and constituting a main air duct whose upper 20 rim trends upward and outward, and fits close to the wall of the chamber, and is furnished with holes for the passage of the supplementary air, substantially as and for the purposes described.

4. In a spray-carbureter, in combination, a chamber having main and supplementary air inlets, a nozzle-structure located therein and 30 presenting a revolving conical top with mixing mechanism, and a porous nozzle-pipe, surrounding the said structure, and consti-

tuting a main air duct whose upper rim trends upward and outward, and fits close to the wall of the chamber, and is furnished 35 with holes for the passage of the supplementary air, and with radial grooves between the said holes for conducting to the inside wall of the nozzle-pipe particles of liquid fuel running down the cylinder wall, 40 substantially as and for the purposes described.

5. In a spray-carbureter, in combination, a chamber having main and supplementary air inlets, a nozzle-structure located therein 45 and presenting a revolving conical top with mixing mechanism, and a porous nozzle-pipe surrounding the said structure, and constituting a main air duct whose upper 50 rim trends upward and outward, and fits close to the wall of the chamber, and presents an annular fillet furnished with holes for the passage of the supplementary air, and with radial grooves between the said holes for conducting to the inside wall of the nozzle-pipe particles of liquid fuel running down the cylinder wall, substantially 55 as and for the purposes described.

In testimony whereof I affix my signature in presence of two witnesses.

GOTTFRIED PLUMM.
